UNITED STATES PATENT OFFICE.

JOHN WINFIELD WOOD, OF MOULTON, IOWA.

ELECTROCHEMICAL PROCESS OF PRODUCING NITROGEN COMPOUNDS.

No. 826,801.

Specification of Letters Patent.

Patented July 17, 1906.

Application filed February 21, 1902. Serial No. 95,072.

To all whom it may concern:

Be it known that I, JOHN WINFIELD Wood, a citizen of the United States, and a resident of Moulton, in the county of Appanoose and State of Iowa, have invented a new and Improved Electrochemical Process for Producing Nitrogen Compounds, of which the following is a full, clear, and exact description.

10 My invention relates to an electrochemical process for producing nitrogen compounds.

The invention consists in the novel steps of the process, as will be hereinafter described and claimed.

15 Reference is to be had to the accompanying drawing, forming a part of this specification, which shows a vertical section through an electrolytic bath embodying my invention.

20 For the purpose of this process I employ an ordinary electrolytic cell with the addition of an aerating device and a siphon.

The electrolytic tank 1 is provided with a distributing-nozzle 2, connecting with a 25 blower or equivalent device 3 for the purpose of forcing air-bubbles through the electrolytic fluid. The cathode is shown at 4 and the anode at 5, the same being supported upon their respective pedestals 6 and 7 and 30 connected, by means of insulated wires 8 and 9, with the dynamo 14. The siphon 10 is provided with a horn-shaped end 11, disposed immediately over the anode and with a hand-valve 12. The receptacle 13 is for the purpose 35 of storing the nitrogen compounds formed when the same assume a liquid form. When said compounds assume a gaseous form, however, they may be pumped off by attaching a hose to the siphon 10. If desired, an addi-

40 tional siphon 15 may be placed over the cathode for the purpose of drawing off any compounds which may be formed adjacent to the same. The electrolytic liquid is shown at 16, and the air-bubbles passing 45 through the same are shown at 17. The additional siphon 15 is indicated by dotted lines.

While a solution of nitrogen in water or in acids is normally quite inert, this condition is 50 changed when the liquid is subjected to electrolytic action—that is to say, the passage of the current through the liquid appears to confer peculiar properties upon the nitrogen whereby it is rendered comparatively ener-

getic and capable of forming compounds not 55 formed in the absence of the current.

The operation of my device is as follows: An electrolytic liquid 16, consisting, preferably, of an aqueous solution of nitric acid or sulfuric acid, is poured into the vessel and a 60 current from the dynamo 14 is sent through the solution in the manner usual to an electrolytic process. The air-bubbles 17, which are produced by forcing air under pressure through the liquid, serve to aerate the same 65 thoroughly and in that manner to charge it with more or less nitrogen. As the current flows through the liquid the liquid is decomposed, oxygen is liberated at the anode, and hydrogen at the cathode. The oxygen thus 70 liberated unites with the nitrogen present, forming nitric acid, (HNO₃), while the hydrogen disengaged similarly unites with the nitrogen present, forming hydrate of ammonia, (NH₃·HO). The result is therefore 75 that nitric acid is formed around the anode and hydrate of ammonia around the cathode, either or both of which compounds may be siphoned off. The process is conducted at 80 ordinary temperatures. The electrolytic fluid around the anode is constantly drawn off by the siphon, so that the operation is continuous. Of course the electrolytic fluid must be renewed, which is done, preferably, by adding water thereto. The nitrogen which is thus 85 constantly removed from the liquid is replenished by the nitrogen of the air as said air passes in the form of bubbles upward through the liquid. A comparatively minute quantity of nitric acid may be used at the 90 start, the air furnishing all of the nitrogen afterward needed.

The amperage and voltage of the current used may be varied within considerable limits, and the apparatus will work at any ordinary temperature. I find that ordinary water reasonably pure and at a temperature of 86° Fahrenheit is suitable for the purpose and that the use of an acid is not strictly necessary. If the use of an acid be desired, a 100 small quantity will suffice.

The nitrogen compounds thus formed are useful for the manufacture of fertilizers and for various other purposes.

In employing this process various potentials and amperages may be employed, depending upon the sizes of the plates and containing vessel and the distances apart of the

plates. One volt and a current strength of one-tenth of an ampere are sufficient for producing the compounds upon a small scale. When, however, the process is used upon a 5 large scale, the amperage may be greatly increased, though in general the voltage should not be very high. All that is absolutely necessary is that the electromotive force must be greater than any counter-electro force of the 10 electrolyte. By varying the space separating the electrodes and by varying the areas of the electrodes the process can be performed successfully with almost any number of volts and amperes.

15 The device is simple and efficient, and its operation is very cheap, owing to the fact that the air used in maintaining the quantity of nitrogen in the liquid costs nothing.

In the carrying out of the process the chemical activity of the nitrogen is greatly increased by the passage of the electric current through the solution, while the forcing of air under pressure through the solution renders the solution mechanically active, both of 20 which tend to the completeness and effectiveness of the process, besides resulting in the more rapid production of the compounds of nitrogen.

Having thus described my invention, I 30 claim as new and desire to secure by Letters Patent—

1. An electrochemical process for making nitrogen compounds, which consists in continuously charging a liquid electrolyte with 35 air under pressure, to furnish it with an excess of nitrogen, and subjecting the liquid to

the action of an electric current to dissociate the liquid, and removing the nitrogen and other compounds thus formed.

2. An electrochemical process for making 40 nitrogen compounds, which consists in preparing an aqueous solution of nitrogen, continuously charging the solution with air under pressure, and subjecting the solution to the action of an electric current to dissociate 45 the solution, and removing the nitrogen and other compounds thus formed.

3. An electrochemical process for making 50 nitrogen compounds, which consists in causing a liquid electrolyte to continuously absorb gaseous nitrogen, sending an electric current through the electrolyte at ordinary temperatures, for the purpose of dissociating the liquid and liberating the products of electrolysis, and finally carrying off the nitrogenous compounds.

4. An electrochemical process for making 55 nitrogen compounds, which consists in continuously charging water with air under pressure, to provide it with an excess of nitrogen, 60 sending an electric current through the water, to dissociate the water and liberate the nitrogen and other products, and finally carrying off at the anode and cathode, respectively, the nitrogen and other compounds formed. 65

In testimony whereof I have signed my name to this specification in the presence of two subscribing witnesses.

JOHN WINFIELD WOOD.
